PRINTING PRESS

Curtis S. Crafts, Oak Park, Ill., assignor to Goss
Printing Press Company, Chicago, Ill., a cor-
poration of Illinois

Application July 22, 1930, Serial No. 469,673

5 Claims. (Cl. 101—378)

The invention relates to new and useful improvements in printing presses and more particularly to such improvements in rotary printing presses optionally adaptable to print either in one 5 or a plurality of colors and with or without late news or sealing devices or the like.

Objects and advantages of the invention will be set forth in part hereinafter and in part will be obvious herefrom, or may be learned by practice with the invention, the same being realized and attained by means of the instrumentalities and combinations pointed out in the appended 10 claims.

The invention consists in the novel parts, constructions, arrangements, combinations and improvements herein shown and described.

The accompanying drawings referred to herein and constituting a part hereof, illustrate one embodiment of the invention, and together with the 20 description, serve to explain the principles of the invention.

Of the drawings:—

Fig. 1 is a longitudinal fragmentary section through a rotary printing press plate cylinder 25 made in accordance with the present invention;

Fig. 2 is a view similar to Fig. 1 with the plate securing means arranged to secure a single narrow plate on the cylinder;

Fig. 3 is a fragmentary end view of the cylinder 30 shown in Figs. 1 and 2, certain parts being shown in section;

Fig. 4 is a fragmentary plan view of the preferred embodiment; and

Fig. 5 is a diagrammatic side elevation of a press 35 constructed and operative in accordance with the present invention.

An object of the invention is to provide a press of relatively few members and of simple and compact construction for printing either multi-color 40 supplements or webs in one color and optionally printing a late news or sealing strip along the edge of a wide web or along the edges of the two halves of a wide web, the press having also a capacity for straight or collected runs and for 45 printing on different width webs.

More particularly the invention provides a simple and compact press adapted optionally to run a straight color supplement on a narrow width web, or to run regular editions on a plurality of webs, utilizing some of the color plate cylinders for printing one or more late news or sealing strips when the regular editions are run.

As exemplarily embodied, the press has two, or 50 a plurality of, perfecting printing units, each unit

comprising two printing couples. One printing couple has an impression cylinder and a coacting plate cylinder provided with means for holding either a narrow set of plates, (generally used for color printing), or a wide set of plates (generally used for regular editions). The other printing couple comprises an impression cylinder and two plate cylinders. One of these plate cylinders likewise is capacitated to hold either a narrow or a wide set of plates, and the other plate cylinder having means for holding a narrow set of plates and alongside thereof means for holding devices for printing a late news strip or sealing strip upon and adjacent to the edge of a wide web.

The color supplement web is passed through both of the units and is printed in one color on one side and in black and three colors on the other side. In regular editions each couple perfects its own wide web, and the extra color plate cylinder may be used to print the late news or sealing strip, as elsewhere fully described.

It will be understood that the foregoing general description and the following detailed description are exemplary and explanatory of the 25 invention but are not restrictive thereof.

Referring now in detail to the embodiment of the invention, illustrated by way of example in the accompanying drawings, one embodiment of the invention is shown in Fig. 5 of the drawings. 30 Two printing units 6 and 7 are shown, adapted to cooperate to perfect a web in multicolor, or, alternatively, each is capacitated to perfect a web in one color. The webs may thereafter be associated and otherwise handled as desired.

The printing unit 7 comprises one printing couple having a plate cylinder 10 and a coacting impression cylinder 10^a, and the other printing couple comprises an impression cylinder 11^a and two coacting plate cylinders 11 and 12. The term 40 printing couple is used in the sense of coacting cylinders capable of printing one side of a web.

The printing unit 6 is of similar construction and arrangement, one printing couple comprising an impression cylinder 13^a and a plate cylinder 13, and the other printing couple comprising an impression cylinder 14^a and two coacting plate cylinders 14 and 15.

A folding mechanism for the printed webs is 50 shown somewhat conventionally at 9. The folder may be of any known or suitable form, and is shown as including one or more formers and cross-folders. Suitable web slitting means, turning bars, or other web handling and associating 55

devices may be employed as found necessary or desirable in handling webs of different widths or different numbers, and in producing various desired products.

- 5 In Fig. 5 the exemplified press is shown arranged to print in multicolor, which is usually done on a narrow web, as in printing the ordinary color supplement. The web 8 passes through the printing couple 10, 10^a and is printed 10 in black on one side and it then passes over guide rollers 16, 17 and 18, through the printing couple 11, 11^a, 12 and is printed in two colors on the other side. The web then passes to the printing couple 14^a, 14, 15 and is printed in two more 15 colors on the last-mentioned side, thus perfecting the web in black on one side and in black and three colors on the opposite side.

To perfect a web in one color in either of the printing units, and if no late news or sealing strip is printed, the web is passed for instance through the printing couple 10, 10^a to be printed on one side and through the printing couple 11^a, 11, 12 to be printed upon the opposite side. In this case the cylinder 12 would not be plated. 25 The cylinder 12 could be plated to print a tint or an additional color.

In accordance with one feature of the invention, when a web is perfected in one color, the extra plate cylinder, such as the cylinder 12, is utilized for printing a late news strip or sealing strip adjacent to and along the edge of a wide web, which has been perfected in one color by the other impression and plate cylinder of the unit. With this in view, the cylinder 12 is provided with means for holding a set of narrow plates, as in color printing, together with means for holding a plate for printing a late news strip or sealing strip. This cylinder can also carry a plate for printing a second late news strip alongside and at or near the middle of, the web, the web being usually slit and associated and folded.

The other printing unit can be run in like manner, and the two webs can be associated if desired at the guiding roller 18, or elsewhere as desired, and the associated webs may be slit or turned, or both, as desired, being then directed to the folder.

Suitable printing plates, varying in size for wide and narrow webs, and of suitable number for the particular press, will be employed, and these may be widely varied with different embodiments of the invention. The embodiment of late news or sealing strip imprinting means may likewise be widely varied as may be found desirable.

55 The impression and plate cylinders of the printing units are shown in Fig. 5 only conventionally, and may be of any known or suitable construction, and the wide and narrow plating of the cylinders may be effected by any desired means. Accordingly, the plate holding and adjusting means employed on the plate cylinders to hold either narrow or wide plates, for the color supplement or straight editions, may be of any known or other suitable form.

65 As previously indicated, in accordance with certain features of the invention, cylinders 12 and 15 are used to take the narrow plating for printing color supplements and for carrying alongside thereof the means for printing the late news or sealing strips on regular runs. Accordingly, in the embodied means for holding the narrow set of color plates, cylinder 12 is provided with a usual fixed plate clamp 21, extending circumferentially and centrally of the cylinder, 70 which cooperates with movable clamps 22, of

usual construction. Near one end of the cylinder, adjustable clamps 23 are provided which secure plates 24 and 25 on the cylinder in the usual manner.

Cylinder 12 is also provided with movable plate clamps 26 and with adjustable clamps 27 which secure plates 28 and 29 on the cylinder. Clamps 27 are resiliently urged inwardly by means of screw rods 30 and nuts 31 which compress springs 32 against the lock-up plate 33. 10 When using the cylinder for straight color runs, plate 28 is pressed inwardly by clamps 27 and, in turn, presses clamps 26 inwardly to secure plate 29 on the cylinder between clamps 21 and 26. 15

In the embodied means for holding and positioning the late news or sealing strip printing devices, narrow marginal plates are positioned about the cylinder, outside the narrow set of plates, and adjacent the margin of a wide web, 20 and are held between a permanent marginal clamp 34 and the regular plate clamp 27, in the usual manner. Clamps 34 are fastened to the cylinder near its end by screws 35. Clamps 27 are moved outwardly of the cylinder to secure 25 the marginal or seal strip plate 36 between them and the clamps 34, as shown in Figure 2. For this purpose, compression springs 37 surround screw rods 30 and are pressed against the clamps 27 by nuts 38 slidably in the grooves 39. 30

When a second seal strip is to be printed on the other longitudinal half of the web, as shown in Figure 2, a dummy plate 40 may be used, and a plate 41 is formed with a printing surface comprising only the seal strip 42 and margin strip 43. These plates are secured to this half of the cylinder by plate clamps 21, 22, and 23. This arrangement of the plates places the seal strip in the same relative position on one half the web, as that of plate 36 on the other half of the web. 40

The invention in its broader aspects is not limited to the specific mechanisms shown and described but departures may be made therefrom within the scope of the accompanying claims without departing from the principles of the invention and without sacrificing its chief advantages. The term "black" as used in the specification and claims denotes a single color, which, however, is usually black. 45

What I claim is:—

1. A printing cylinder for a rotary newspaper press for printing in multi-color or alternatively perfecting a web and printing a marginal seal strip, said printing cylinder having a pair of fixed plate securing means and a movable plate clip to clamp a plate between it and either fixed plate securing means. 55

2. A printing cylinder for a rotary newspaper press for printing in multi-color or alternatively perfecting a web and printing a marginal seal strip, said printing cylinder having a pair of fixed plate securing means on said cylinder and a movable plate clip normally positioned closely adjacent to one of the fixed plate securing means to clamp a full page plate between it and a fixed securing means or a narrow plate between it and the other fixed securing means. 60

3. A printing cylinder for a rotary newspaper press for printing in multi-color or alternatively perfecting a web and printing a marginal seal strip, said printing cylinder having a pair of fixed plate securing means, one of said securing means being positioned centrally of said cylinder while the other is closely adjacent to the end of the cylinder, a movable plate clip closely adja- 70

cent to the clip near the end of the cylinder, a freely movable plate clip between the movable plate clip and the centrally positioned clip whereby full page plates or a narrow plate may be secured on the cylinder.

4. A printing cylinder for a rotary newspaper press for printing in multi-color or alternatively perfecting a web and printing a marginal seal strip, said printing cylinder having a fixed plate securing means spaced somewhat more than two page widths apart and a pair of movable plate clips between said fixed securing means to clamp a pair of full width plates or a narrow plate on said cylinder.

5. A printing cylinder for a rotary newspaper press for printing in multi-color or alternatively perfecting a web and printing a marginal seal strip, said printing cylinder having a pair of fixed plate securing means, said securing means being positioned somewhat more than two page widths apart, a movable plate clip between said fixed securing means, a freely movable clip between the movable clip and one of the fixed securing means whereby two full width plates or a single plate may be secured on the cylinder.

CURTIS S. CRAFTS.
